MILK COOLER

James Gregory and Leo A. Babcock, Cattaraugus,
N. Y., assignors to Oakes & Burger Co., Cattaraugus, N. Y., a corporation of New York

Application April 23, 1940, Serial No. 331,193

7 Claims. (Cl. 257—180)

This invention relates to improvement in milk coolers of the kind wherein, as a sanitary measure, the cooling element is incased in a shell having cover sections which are adapted to be normally closed but which may be opened when desired to obtain access to the cooling element and other internally located parts.

In the use of this type of cooler, contrary to hygienic procedure, it has frequently been the practice to leave the cover sections open or to remove them entirely, thereby exposing the films of milk flowing over the cooling element directly to the dust, bacteria and other impurities present in the air in the vicinity. The principal object of the present invention, therefore, is to prevent contamination of the milk in this manner, this object contemplating a cooler which is so designed that it can be rendered operative only by properly closing the cover sections. Improper use of the cooler is thus prevented.

A further object is to provide for facility in cleaning the cooler and in assembling and disassembling the parts.

A still further object is to provide a cooler which is simple and compact in design and which occupies a minimum of space.

The invention is illustrated in the accompanying drawings in which:

Figure 1 is a front elevation of a cooler embodying the features of the invention.

Figure 2 is a top view thereof.

Figure 3 is an enlarged detail section taken along line 3—3 of Figure 1.

Figure 4 is a detail section taken along line 4—4 of Figure 3.

Figure 5 is a detail section taken along line 5—5 of Figure 4.

Figures 6 and 7 are views in elevation of the opposite ends of the cooler.

Figure 8 is a detail view of one of the hinge connections of the cover sections.

Figure 9 is an enlarged vertical section taken along line 9—9 of Figure 1.

Figure 10 is a vertical section taken along line 10—10 of Figure 9.

The cooler, as illustrated, includes a cooling element 12 (Figure 9), an upper distributing trough 13, a lower collecting trough 14 and cover sections 15 and 16. The said cover sections, the end walls 17 and 18 of the cooling element and the collecting trough 14 provide a cooling chamber 19. The side flanges 20 of the cover sections abut the vertical edges of the end walls 17 and 18 of the cooling element and have abutting ex-

55 tensions 20a which rest upon the top edges of the

said end walls (see Figure 6); and the top flange 21 of the cover section 16 overlaps the corresponding flange of the cover section 15. The milk, or other liquid to be cooled, is introduced into the trough 13 through an inlet opening 22 formed in the top flange of the cover section 16 and is discharged from the trough through two series of perforations 23, one series of perforations being located at one side of a central division fin 24 formed on the top of the cooling element and the other series of perforations being located at the opposite side of the division fin. The liquid which is discharged through the perforations is thus caused to flow down the opposite sides of the cooling element in thin films and collects in the lower trough 14 from which it passes through an outlet connection 25. Preferably the distributing trough 13, as shown in Figure 10, is detachably supported above the cooling element 12 by extensions 13a which are 20 insertable in, and which rest upon the bottoms of, vertical slots 13b formed in the end walls 17 and 18 of the cooling element.

The cooling element may be formed in any suitable manner. As illustrated, it consists of 25 two metal sheets having uniformly spaced aligned corrugations, the facing abutting peak portions of the corrugations being soldered together as indicated at 26 to provide a vertical series of horizontally extending tubes. At one 30 side of the cooling element alternate of the abutting tube walls are deformed, or cut away, to provide connecting passages 27 (Figure 10) while at the opposite side the intermediate walls are deformed, or cut away, to provide connecting 35 passages 28. A sinuous path is thus provided for the cooling medium which is adapted to enter the cooling element through an inlet pipe 29 and leave it through an outlet pipe 30. The forming of the connecting passages 27 and 28 in the 40 manner described spaces portions of the ends of the tubes from the end walls 17 and 18. To close the openings thus formed, the pockets at the ends of, and between the crests of, the tubes may, as shown, be filled with solder 28a. Downwardly and inwardly inclined ribs 28b at the lower end of, and at opposite sides of, the cooling element intercept any liquid flowing over the cooling tubes adjacent the end walls 17 and 18 and direct it away from the said walls. Entry 45 of such liquid into the trough 14 is thus insured.

The pipe 29 is connected by an elbow 31 (Figure 1) to a vertical extension 32 while the pipe 30 is connected by an elbow 33 to a vertical 55

extension 34. Cooling fluid is supplied to the extension 32 through a flexible tube 35 and discharges from the extension 34 into a similar tube 36. The inlet and outlet pipes 28 and 30, 5 the elbows 31 and 33 and the vertical pipe extensions 32 and 34 may be, and preferably are, utilized in mounting the cooler, the said extensions serving as trunnions and fitting in openings 37 formed in the upper and lower arms 38 10 of a bracket 39 which is adapted to be mounted upon a wall or other convenient supporting surface. The construction described enables the cooler to be swung to various positions, as indicated in Figure 2. In order to hold the cooler 15 in such positions, it is preferred that a flange 40 on the elbow 33 be formed with indentations 41 (Figures 4 and 5) which headed elements 42 carried by the upper arm of the bracket 39 may enter and hold the cooler against accidental 20 angular displacement.

The cover sections 15 and 16 are intended to be closed during use of the cooler but are connected to the end wall 17 of the cooling element by hinges 43 so that they may be opened to provide access to the cooling element and the trough 13. Preferably the hinges 43 are of the hook-and-eye type in order that the cover sections may be completely detached, if desired. In accordance with the invention the lower marginal 25 edges of the cover sections are inturned to provide flanges 44 for cooperating with flanges 45 formed on the trough 14. The flanges 44 curve inwardly and upwardly while the flanges 45 curve outwardly and downwardly. The two pairs 30 of flanges interfit, therefore, so that the collecting trough is supported by the cover sections in the desired relation with respect to the cooling element, the engagement of the said flanges serving to hold the cover sections closed. Free movement 35 of the trough 14 lengthwise to permit its removal and replacement and the opening of the cover section is, however, permitted, a handle 46 being fixed to the outer end of the trough to enable it to be manipulated with facility.

45 From the foregoing it will be apparent that the collecting trough 14 is supported in cooperating relation with respect to the cooling element by the lower inturned marginal edges of the cover sections and that the said trough can only 50 be so supported when the cover sections are closed. Use of the cooler either with the cover sections open or with them removed is thus prevented, it being noted that to ready the cooler for use the cover sections must be first closed 55 and the collecting trough then inserted in the manner of a drawer. Referring to Figure 9, it will be noted that the flanges 44 provide channels along the lower edges of the cover sections. Any moisture of condensation which may form 60 upon the cover sections will drain into these channels and hence will be prevented from entering the trough 14.

The construction described has the advantage that the cooling of the liquid is carried out 65 hygienically in a closed chamber from which dust, bacteria and other impurities present in the air are for the most part excluded. A further advantage obtained is that ready access may be had to the parts of the cooler for purposes of 70 inspection and cleaning, the swivel mounting of the cooler enabling it to be swung against the supporting wall when not in use so as to occupy a minimum of space.

We claim as our invention:

75 1. A liquid cooler of the character described

including a cooling element over which the liquid to be cooled is caused to flow, a casing for said element, said casing having a section which is adapted to be closed during use of the cooler but which may be opened to provide access to said 5 element, a receptacle into which the cooled liquid drains and means which is operative only when said section is closed for supporting said receptacle in predetermined relation with respect to said element. 10

2. A liquid cooler of the character described including a cooling element over which the liquid to be cooled is caused to flow, a casing for said element, said casing having companion cover sections which are adapted to be closed during use 15 of the cooler but which may be opened to provide access to said element, a receptacle into which the cooled liquid drains and means which is operative only when said sections are closed for supporting said receptacle in predetermined relation with respect to said element. 20

3. A liquid cooler of the character described including a cooling element over which the liquid to be cooled is caused to flow, a casing for said element, said casing having companion cover sections which are adapted to be closed during use 25 of the cooler but which may be opened to provide access to said element, ledges provided upon said sections and a receptacle into which the cooled liquid drains, said receptacle being removably supported upon said ledges. 30

4. A liquid cooler of the character described including a cooling element over which the liquid to be cooled is caused to flow, a casing for said element, said casing having companion cover sections, hinge mountings for said sections, said sections being adapted to be closed during use 35 of the cooler but being movable to open positions to provide access to said element, flanges along the lower edges of said sections and a receptacle 40 removably supported by said flanges in predetermined relation with respect to said element and into which the cooled liquid drains, said receptacle having flanges which cooperate with the flanges on said sections only when the latter 45 are in their closed positions.

5. A liquid cooler of the character described including a cooling element over which the liquid to be cooled is caused to flow, a casing for said element, said casing having companion cover sections, hinge mountings for said sections, said sections being adapted to be closed during use 50 of the cooler but being movable to open positions to provide access to said element, flanges along the lower edges of said sections and a receptacle 55 supported by said flanges in predetermined relation with respect to said element and into which the cooled liquid drains, said receptacle having flanges which cooperate with the flanges on said sections only when the latter are in their closed 60 positions and which are adapted to hold said sections closed.

6. A liquid cooler of the character described including a cooling element over which the liquid to be cooled is caused to flow, a distributing 65 trough into which the liquid is initially introduced, a casing for said element and trough, said casing having companion cover sections which are adapted to be closed during use of the cooler but which are movable to open positions to provide 70 access to said element and trough, ledges along the lower edges of said cover sections and a collecting trough supported by said ledges in predetermined relation with respect to said element and into which the cooled liquid drains. 75

7. A liquid cooler of the character described including a cooling element over which the liquid to be cooled is caused to flow, a distributing trough into which the liquid is initially introduced, a casing for said element and trough, said casing having companion cover sections which are adapted to be closed during use of the cooler but which are movable to open positions to pro-

vide access to said element and trough and a receptacle into which the cooled liquid drains, said receptacle being removably supported by said sections only when the latter are in their closed positions.
